CORNER HOLDING DEVICE

Floyd J. Kendall, Springfield, Ohio, assignor to
 The Springfield Metallic Casket Co., Inc.,
 Springfield, Ohio, a corporation of Ohio

Application February 13, 1946, Serial No. 647,354

6 Claims. (Cl. 27—2)

1

My invention relates to corner holding device for attaching decorative escutcheon plate to the exterior of a casket without disclosure from the exterior of the attaching means.

It is the object of this invention to provide attaching means for the escutcheon plates and in particular corner escutcheon plates.

It is an object to provide such an attaching means that cannot be seen from the exterior of the casket, that will be firmly locked to the casket and that will be self-aligning and that will accommodate the irregularities of manufacture so that a tight joint can be made between the face of the casket and the engaging surfaces of the escutcheon plate.

Heretofore in the art the attachment of escutcheon plates has presented the problem of unsightly retaining bolts and screws which are frequently of different metals from the highly decorative escutcheon plates and, therefore, are conspicuous. The escutcheon plate is weakened by the piercing of the plate to receive the attaching bolts or screws. Such attaching bolts or screws did not accommodate themselves to the necessary irregularities resulting from the manufacture of thin pressed metal or cast escutcheon plates. The attaching means did not lend themselves readily to any preassembly operation nor were they adapted particularly for the position of escutcheon plates on corners of caskets.

It is the object of this invention to overcome the defects of prior art structure and particularly to provide a ready means of preassembly and accommodation of different sizes and variations of casket and escutcheon plate constructions.

It is also an object to provide means of aligning the escutcheon plate with the corner of the casket.

Referring to the drawings,

Figure 1 is a horizontal section through a corner of a casket and a corner escutcheon plate showing in plan view the attaching means;

Figure 2 is a perspective of the same structure;

Figure 3 is a detailed view with the attaching means partly in section;

Figure 4 is a section on the line 4—4, looking in the direction of the arrows, of Figure 1.

Referring to the drawings in detail, 1 designates an escutcheon plate having diverging arms with casket wall engaging ends 2 to engage the walls 3 and 4 of a casket; these two walls 3 and 4 form a corner 5 of the casket. The escutcheon arms are connected by a central portion 6 constituting a corner generally opposite the corner 5 of the casket. The corner 5 of the casket is pro-

vided with a bolt aperture 7 in which is mounted a retaining bolt 8 the inner end of which is threaded at 9 to receive the nut 10. The nut engages with a substantially D-shaped or channel shaped aligning corner plate 11 which engages with its tapered side edges the inside walls 3 and 4 of the casket. The outer end of the bolt 8 is provided with a crosshead 12 which has been introduced through the cam slot 13 of the escutcheon plate retaining member which is a U-shaped body having a back plate 14 and arms 15 in which are cut the slots 13. The slots are extended into a semicircular recess 16 for receiving the crosshead 12 of the bolt 8. This retaining member is attached by welding as at 17 to the inside of the escutcheon plate corner 6. It will be noted that the peripheral edge of each arm of the escutcheon plate on the concave side thereof lies in a plane which may be called a "mounting plane." These planes are angularly related and, when the plate is mounted on the corner of a casket or the like, coincide with the outer surfaces of the casket walls. It will also be observed that the arms 15 of the retaining clip terminate between the escutcheon plate on its concave side and the planes as defined by the inner edges of the arms 2 as described above.

It will be noted that the use of the cam slot 13 and recess 16 with an annular crosshead 12 provides means for locking the parts together and accommodating irregularities.

In assembling, the cam attaching means is spot welded to the interior of the escutcheon plate. The crossbar 12 is dropped in the cam slot, the bolt 8 is inserted through the opening 7 and thence through the corner retainer 11 and the nut 10 is turned up to lock the parts together. The result is that there is no visible attaching means from the exterior of the casket and the escutcheon plate fits snugly to the exterior surface of the casket irrespective of any irregularities in manufacture.

It will be understood that I do not wish to be limited to the specific structure and arrangement shown in the drawings but desire to comprehend such modifications thereof as come within the scope of the claims.

Having thus fully described my invention, what I claim as new and desire to secure by Letters Patent is:

1. In a corner escutcheon plate for a casket or like member, means for attaching said escutcheon plate to the corner of a member, said means comprising a U-shaped clip secured to the inside of the plate and having slots therein inclined with

the open ends toward said plate, a T-shaped bolt having its crosshead in said slots and its shaft adapted to extend through said corner, and a channel shaped clip having a hole to receive said bolt and adapted to engage the inside of the corner of the member, the said means thus providing for a concealed support for said plate.

2. In a corner escutcheon plate for a casket or like member, a U-shaped plate having cam slots in the arms thereof and mounted on the inside of the escutcheon plate, a triangular channel shaped bolt support having an aperture for receiving the bolt mounted on the inside of a corner of the member, the said corner having an aperture for receiving a bolt, a T-shaped bolt having its crosshead mounted in said cam slot and its shaft extending through the aperture in the corner and the aligned aperture of the triangular bolt support, and a clamping nut mounted on the inner end of said bolt whereby the escutcheon plate is adjustably clamped and locked to the exterior of the member and said attaching means is completely concealed from the exterior of the plate and member.

3. In a corner escutcheon plate for a casket, said plate being concave internally in cross section and the periphery of the plate on its concave side defining mounting planes at the same angularity as the sides of the casket forming the corner for receiving the plate, a U-shaped slotted attaching means mounted on the interior of the corner of the plate and extending to a point between the mounting planes and the inside of said plate, and a T-shaped bolt having its crosshead mounted in said slot and its inner end extending through the line of intersection of said mounting planes and threaded to receive a nut.

4. In a corner escutcheon plate for a casket, said plate being concave internally in cross section and the peripheral edge of the plate on its concave side defining angularly related mounting planes, a U-shaped slotted attaching means mounted on the interior thereof and extending to

a point between the said mounting planes and the concave side of said plate, a T-shaped bolt having its crosshead mounted in said slot and its inner end threaded to receive a nut, the casket on which said plate is to be mounted having a hole to receive said bolt, and an interiorly disposed channel shaped bolt support inside the corner of the casket and also having an aperture to receive said bolt.

5. In a corner escutcheon plate for a casket, said plate being concave internally in cross section, a U-shaped slotted attaching clip mounted on the inside of the corner of said escutcheon plate, a T-shaped bolt having the transverse portion thereof mounted in said slot, the casket for receiving said plate on the corner having an aperture for receiving said bolt, and a channel shaped clip on the inside of the corner of the casket and also having an aperture for receiving said bolt.

6. In a corner escutcheon plate for a casket, said plate being concave internally in cross-section, a slotted attaching clip mounted on the inner corner of said plate and having an enlarged recess at the bottom of the slot, a cylindrical bolt having a cylindrical crosshead adapted to engage with the enlarged recess at the bottom of said slot of the attaching clip, and means on the inner end of said bolt for attaching it to the interior of a corner of a casket, said casket having an aperture for receiving said bolt.
